UNITED STATES PATENT OFFICE

HAMPTON K. SMITH, OF UNION, SOUTH CAROLINA.

LIQUID-EJECTING APPARATUS.

950,410.

Specification of Letters Patent. Patented Feb. 22, 1910.

Application filed March 6, 1908. Serial No. 419,556.

To all whom it may concern:

Be it known that I, HAMPTON K. SMITH, a citizen of the United States, and a resident of Union, Union county, South Carolina, have made certain new and useful Improvements in Liquid-Ejecting Apparatus, of which the following is a specification.

This invention is an improvement in apparatus for dispensing liquids, adapted for use in ejecting soda water syrups and mineral waters and other liquids, and the invention consists in certain novel constructions and combinations of parts as will be hereinafter described and claimed.

In the drawings, Figure 1 is a front elevation of my improved apparatus. Fig. 2 is a vertical longitudinal section thereof, the pumping piston being shown in its lowermost position. Fig. 3 is a detail view of the piston showing the valves thereof. Fig. 4 is a section somewhat similar to Fig. 2, and showing the piston at the end of its pumping stroke. Fig. 5 is a horizontal section showing the circuit closing mechanism. Fig. 6 is an enlarged detail view illustrating the construction at the upper end of the cylinder and the connection between the contacts thereof and the casing. Fig. 7 is a detail partial cross section of the cylinder through the contacts thereof. Fig. 8 is a detail perspective view showing the rail of the casing and the cover plate thereof detached parts being broken away and others shown in section. Fig. 9 is a detail top plan view showing the cylinder partly in section and partly within the face plate, and Fig. 10 is a diagrammatic view illustrating the circuits.

In the construction shown, I illustrate a jar A which may be a syrup jar or other suitable liquid containing vessel, and this jar is provided at or near its upper end with a nipple A' which inclines upwardly toward its outer end. This nipple A' affords means for the introduction of a cylinder B which extends through the nipple A' into the jar and preferably to the bottom of the jar resting at its lower end on the jar bottom and receiving at its upper end a ring or band C threaded on the cylinder B and bearing against a face plate D. By this construction the cylinder is supported at its inner lower end upon the bottom of the jar and at its outer end upon the face plate D, thus firmly supporting the cylinder in position for use.

At its lower end, the cylinder has an opening B' through which the liquid may pass from the jar into the lower end of the cylinder and a piston E operates within the cylinder and the lower end of the piston has check valves E' and E'' to permit the passage of the liquid through the piston, and the piston has its rod F extending within a solenoid G, so the piston may be operated as the magnet is energized. The magnet G provided in connection with the cylinder, preferably fits within the upper end of the cylinder and is shown as a double magnet, that is to say, having magnet portions G' and G'' at its opposite ends. The piston rod F operates within the magnet, is made tubular for the passage of the liquid, is arranged at its upper end to discharge through the bore of the magnet to a tube H leading to the outlet nozzle and near its lower end the rod F is slotted at F' to permit the liquid to pass through the valves of the piston and thence through the opening F' into the hollow piston rod whence it may be discharged on the upward stroke of the piston to the tube H and thence to the nozzle.

In the general operation of this construction, when the parts are in the position shown in Fig. 4, that is to say, with the piston E up against the magnet, a circuit is closed to energize the magnet portion G'. This will operate to draw the unslotted part of the piston rod F toward the center of the coil G' and to force the piston to its lowermost position to permit the cylinder to fill above the piston and then a circuit is closed to energize the magnet portion G'' which will operate upon the core or piston rod F and readjust the piston to the position shown in Fig. 4, such operation forcing the liquid above the piston out through the tube F and connecting tube H, as desired. I thus provide, in connection with the cylinder and the pumping piston operating therein, magnets which can be independently energized to operate the piston first in one direction and then in the other and I construct this magnet in solenoid form so the piston rod may form the core of the magnet and the liquid can be discharged through the said piston rod and through the magnet, thus furnishing a simple and compact construction, as shown. Feed wires K, and K' which may lead from a street service or other source of electrical supply con-

nect with the casing at K^2 , K^3 and extend thence as shown in Fig. 5, and in the dia-grammatical views Fig. 10. The casing or frame has a bar I carrying the spring con-5 tact points I' , I^2 , I^3 , I^4 , and I^5 . The cylin-
10 der is provided with contact points J' , J^2 , J^3 ,
 J^4 , and J^5 corresponding respectively with
15 the contacts I' , to I^5 and moving into elec-
trical connection with their said respective
10 contacts when the cylinder is moved into
position for use as shown in Figs. 2, 4 and 6.
The intermediate contact point J^3 is
15 branched by a wire i' on the feed wire K'
and the contact point J' is branched by a
wire i^2 and wire N^3 on the feed wire K .

The cylinder B carries a small lamp L
which is interposed in an open circuit whose
terminals are connected with the contacts J' ,
and J^2 . The winding of the solenoid G^2 has
20 its terminals g^2 and g^3 connected with the
contact points J^3 and J^5 , and the winding of
the solenoid G' has its terminals g and g'
connected with the contact points J^3 and J^4
respectively. The lamp L and the solenoids
25 as before described are carried by the cylin-
der and the electrical connections between
said lamp and the solenoids and the contact
points J' to J^5 inclusive are all carried by
the cylinder.

30 In connection with the described construc-
tion I provide means for closing the elec-
trical circuits including the lower magnet
 G' , and also for closing the circuit includ-
ing the upper magnet G^2 , and I close these
35 circuits in succession first closing the circuit
of the magnet G' and then closing the cir-
cuit of the magnet G^2 , and when the circuit
including the magnet G^2 is closed I also close
the lamp circuit to light the lamp, this being
40 effected simultaneously with the pumping
stroke of the piston. To this end I provide
a movable circuit closer in the form of a
push button M actuated outwardly by a
spring M' and having at its inner end a
45 portion M^2 which forms a bridge between
the terminals of the two electric circuits
presently described.

The bridge M^2 operates in connection with
50 terminals N , N' and N^2 . The terminal N
connects by a wire N^3 with the feed wire K
and by a wire i^2 with the contact J' . The
terminal N' connects by a wire N^4 with the
contact J^4 and the contact N^2 connects by a
55 wire N^5 with the contact J^2 and by a wire N^6
with the contact J^5 .

The push button M may be curved on its
outer side as best shown in Fig. 10, so a
glass may be pushed against the button to
force the same in to close the circuits. As
60 the button is pushed in, the circuit is first
closed at N , N' . This will close the circuit
including the magnet G' through the wires
 N^3 from the feed wire K and wires N^4 , g' , g ,
and i' to the feed wire K' . A further in-
65 ward movement of the push button will break

the circuit between the supply wires, K K'
and the coil G' and will close the circuit at
 N and N^2 , such circuit including the magnet
 G^2 and being closed through the wires N^3
to the feed wire K , and N^6 , g^3 , g^2 , and i' to
70 the feed wire K' . Thus as the button is
pushed in I first energize the magnet G'
which acting upon the core F will move the
piston to the bottom of the cylinder as shown
75 in Fig. 2 and then the magnet coil G' will
be deenergized due to the interruption of
its circuit in the progressive movement of
the bridge M^2 and the magnet G^2 will be
energized and acting upon the core F will
80 actuate the piston E in its pumping stroke
to force the liquid out. When the bridge M^2
closes the circuit to magnet coil G^2 it will
simultaneously close the circuit N^3 , N^5 and
light the lamp L.

An adjustable stop in the form of a screw
85 F^2 is provided at the lower end of the cylin-
der to limit the downward movement of the
piston and thus enable me to regulate the
amount of liquid discharged at each dis-
charge of the piston.

90 The tubular core F is preferably nickel-
plated on its outer and inner sides, as shown
at F^3 in Fig. 6, or otherwise provided with
a protecting coating to prevent the oxidation
of the said tube or other bad effect from the
95 contact of the metal with the liquid being
dispensed.

The liquid is discharged in the tube H
and thence through a check valve H' to the
nozzle H^2 whence it is discharged to a glass
100 placed below it, as shown in Fig. 4.

The face plate D is provided at its upper
end with a tubular portion D' which is
notched in its upper side at D^2 to receive
the insulating block D^3 on the cylinder and
carrying the contact points J' to J^5 as shown
105 in Fig. 9, and this insulating block D^3 when
fitted in the slot D^2 secures the cylinder from
turning within the face plate and properly
alines the said contact points from J' to J^5
110 with their corresponding contact points I' , I^5
mounted on the frame, the said contact
points I' to I^5 being guarded and protected
by a cover plate I^6 shown detached in Fig. 8
and applied in Figs. 1, 2, and 6.

115 The contact points J' to J^5 are secured
firmly within the insulating block D^3 and
the electrical connections leading from said
contact points to the light L and to the mag-
nets G' and G^2 are within the casing B and
the outward extension B^{10} thereof and thus
out of the way so that they cannot be tam-
pered with by meddlers. An extension B^{10}
is secured on the outer end of the cylinder
and incloses the pipe H and the nozzle H^2
125 and carries at its outer end the lamp L which
is visible through a lens L' , as above shown
in Figs. 2, 4 and 9 of the drawing.

The glass to receive the liquid dispensed
rests upon a shelf O, which may drain
130

through a pipe O' and any leakage from the jar A may discharge through a pipe P as shown in Figs. 2 and 4 of the drawing.

In the operation of my invention, it will be noticed that the liquid is discharged through the solenoid and through the hollow piston rod forming the core of the solenoid magnet, and the piston is operated positively in both directions by the magnet as before described, and in practice the piston may be made of very light material to avoid its gravity operating to any considerable extent in opposition to the magnets.

Manifestly, the invention can be carried out in connection with the single jar as before described or a plurality of said jars may be operated side by side as illustrated in Fig. 1 and this latter arrangement will be found especially useful in soda water fountains and other apparatus for dispensing various kinds of drinks, such for instance as mineral waters.

The tubular portion D' of the face plate fits within the inclined nipple A' of the jar A and projects at its inner end beyond said nipple, as best shown in Figs. 2, 4 and 6, and is threaded at such end at D⁴ to receive a band D⁵ screwed thereon and operating to secure the tube D' firmly within the inclined nipple of the jar A.

As best shown in Figs. 4, 6 and 9, the band C secured on the outer end of the cylinder bears against the face plate D and also operates to secure the extension B¹⁰ to the outer end of the cylinder.

The fountain construction proper disclosed herein, forms the subject matter of a separate application for patent which I am about to file.

40 What I claim is:

1. The combination, of a cylinder, a solenoid in connection with said cylinder, and a piston outside of the solenoid and operating in the cylinder, and having its rod forming the solenoid core and made hollow whereby a liquid may be passed through the hollow piston rod and through the solenoid in which said rod reciprocates, the piston having a passage communicating with that of its rod.

2. The combination with a cylinder, of a solenoid having a pair of magnet portions, and a piston outside of the solenoid and moving toward and from the end thereof and operating in the cylinder and having a hollow piston rod forming the solenoid core, the piston having a passage communicating with that of its rod, and means whereby the opposite magnet portions may be energized 55 to effect a positive movement of the piston in opposite directions.

3. The combination in a liquid ejecting apparatus, of a cylinder, a solenoid in the upper end of the cylinder and having magnet portions, and a piston in the cylinder

and below the solenoid and having a hollow piston rod forming the core of the solenoid.

4. The combination with a cylinder and a piston operating therein and having a hollow rod forming a solenoid core, of a solenoid connected with the cylinder and having outer and inner magnet portions, electrical circuits including said portions, means for closing said circuits in succession, a lamp, and a circuit including said lamp and having 75 a common closer with the circuits of one of the magnet portions.

5. The combination in a liquid ejecting apparatus with a solenoid having two magnet portions, and a pumping piston operated thereby, of a lamp, a circuit including said lamp and one of the magnet portions, a circuit including the other magnet portion, and a circuit closer operating to close said circuits in succession, the circuits being normally open all substantially as described whereby the operation of the circuit closer will act to energize one of the magnets without lighting the lamp and will then operate to energize the other magnet and light the 90 lamp, all substantially as set forth.

6. The combination of a cylinder, upper and lower magnets, a hollow piston rod forming the core of the magnets and having a piston coöperating with the cylinder to 95 form a pump, a switch, and electrical connections between the switch and the magnets and operating to energize the lower magnet and then the upper magnet by a continuous movement of the switch in one direction.

7. An apparatus comprising a cylinder, electromagnets, a piston in the cylinder beyond the electromagnets, a rod extending from the piston in the electromagnets and forming a solenoid core, and circuits controlling the magnets whereby one magnet may be caused to operate the piston in one direction and the other magnet to operate in the other direction, the piston rod being hollow and forming a conduit for the 110 pumped liquid, and the piston having a passage communicating with that of its rod, substantially as set forth.

8. The combination in a liquid ejecting apparatus of a cylinder, an extension connected with the outer end of the cylinder, a lamp at the outer end of said extension, a nozzle and connecting pipe between said lamp and cylinder, a solenoid magnet in the outer end of the cylinder, and a piston having a tubular rod forming the core of the solenoid and discharging at its outer end to the connecting pipe leading to the nozzle at the pumping stroke in the piston.

9. The combination in a liquid ejecting 125 apparatus, of a solenoid having a pair of magnets, a cylinder beyond the end of the solenoid and in close proximity thereto, a piston in said cylinder and a hollow piston rod extending from said piston into the so- 130

lenoid and forming the core thereof, and a conduit for the discharged liquid.

10. The combination of a cylinder, a solenoid in connection therewith, a piston operating in the cylinder and having a hollow rod forming a solenoid, and a conduit for the liquid discharged by said piston, and an

adjustable stop for said piston whereby to regulate the amount of liquid discharged by the piston.

HAMPTON K. SMITH.
